BAG FILLING MACHINE

Austin S. Chandler, Fitchburg, Mass., assignor to
 The Brown Bag Filling Machine Co., Fitchburg,
 Mass., a corporation of Massachusetts

Application October 30, 1936, Serial No. 108,487

18 Claims. (Cl. 226—49)

The invention relates to machines for measuring a quantity of material, introducing the same into a receptacle, closing and sealing the receptacle, and delivering the filled receptacles in orderly fashion. While the present embodiment is adapted specifically to use with fluent material such as powder and granular products introduced into paper bags like envelopes, it may be applied to other uses, as will be readily apparent.

It is an important consideration in such machines to embody them in compact form, owing to the high cost of loft space and especially where installations must be made in high rent districts, as well as to facilitate servicing and tending of a bank of such machines. To this end it is an aim of the present invention to enable the attainment of all necessary operations within a radius reduced to a notable degree, utilizing a vertical main rotating element and having the operative parts of the several stations grouped around this with operative connections so simplified and coordinated that cam details, conveyor features, filling, closing, gumming, folding, and sealing, all involve an extremely small number of parts of simple form, readily accessible and durable construction, while attaining high efficiency in the functioning of the machine. It is an important aim of the invention to enable the arrangement of the path of receptacles around a center beneath the hopper device, so that but little more horizontal area is occupied than is necessary to accommodate an individual stock bin or hopper of reasonable capacity for such a machine. It is also an important object to enable the arrangement of operating elements in a vertical superposed relation, so that vertical space will be utilized better to limit horizontal extension.

It is an important object of the invention to present novel means for accommodating such a machine to various sizes of receptacles without disturbing the operative devices for opening, measuring, closing, sealing, and other details of operative means. A specific aim of the invention is to present a novel and desirable construction in stock-saving means in the form of a trap operative at the filling station to prevent loss of stock, in case of a bag not opened when a charge of stock is discharged, but in addition having peculiar advantages in avoiding restriction of the opening in a bag, or damage, even with very thin paper stock.

Another specific object of the invention is to present a novel construction and mounting for the hopper and measuring device. Another aim of

the invention is to present a highly efficient simple and compact sealing mechanism, that will at the same time serve as a conveyor readily and will enable ordering of the filled receptacles for shipment or otherwise.

A further important general object of the invention is to so design and coordinate the various operative mechanisms that a very small power unit will suffice for its operation. Thus, it has been found practicable to use a motor of $\frac{1}{6}$ horsepower, and $\frac{1}{4}$ horsepower is adequate with good margin for the heaviest and comparatively large packages for handling in such machines.

It is an outstanding valuable characteristic of this invention that in its present embodiment with a hopper of large capacity, it is of such low height that the hopper may be filled or cleaned without the use of a step or ladder; but at the same time the path of the packages and the units operative thereon are at a good height for ready observation, access and servicing, so that it may be set upon a loft floor and the operatives in attendance will be able to attend its normal servicing without assuming awkward positions.

It is also an important aim to enable ready and immediate dumping of the hopper, and its ready cleaning by an operative standing upon the floor, at any time, without requiring disconnection of the operative parts, or dismounting of operative connections, and without the service of a mechanician, notwithstanding the use of a feed device in the hopper.

A special purpose is to present a measure which will operate with a minimum of friction in guides and on the materials measured, to the end that heating by this element and damage to goods thereby is reduced to a marked degree.

It is also an important aim to provide a feed in the hopper which will also operate to efficiently discharge the material to the measure with a minimum of friction.

An object of the invention is to embody a novel bag-presenting means. Another specific aim is to present a novel means to shape the bag and contents preliminary to creasing and closing.

It is also a purpose to construct a novel and effective scoring device. In addition it is sought to embody a novel and desirable gumming unit, and closer operative thereafter. A further object is to present a novel construction in an endless clamp conveyor for insuring the permanent sealing of the bags after leaving the closer.

A further object is the invention of a novel turret support for bags being filled and operated on successively at the respective stations.

- It is a still further purpose to give a novel and effective step-by-step action, with means for avoiding shocks in the movements and to avoid irregularity of movement.
- 5 An additional aim is to present novel construction in securing coordinated movements of certain elements having movements of different timing but in part simultaneous.
- 10 A further aim is to so coordinate these elements that a minimum power consumption is involved. Another object is to provide a novel package carrier in such a machine.
- 15 A further object is to present a novel simple means for opening bags with minimized liability of the opener to strike the edge of the bag. Still another object is to give a novel control construction in a package holder and release.
- 20 Additional objects, advantages and features of invention reside in the construction, arrangement and combination of parts involved in the embodiment of the invention, as will appear from the following description and accompanying drawings, wherein
- 25 Figure 1 is a front elevation of a machine embodying the invention.
- 30 Figure 2 is a schematic diagram of the station sequence.
- 35 Figure 3 is a detail vertical section of the clutch and drive connections;
- 40 Figure 4 is a vertical sectional view on the axis of the shaft 16 of Figure 3.
- 45 Figure 5 is a side elevation of the machine.
- 50 Figure 6 is a vertical transverse section of the table and knee bracket.
- 55 Figure 7 is a detail of the connection for shifting the bag box.
- 60 Figure 8 is a top view of the machine with the top or platform removed, partly in section with parts broken away over the index bar, and with portions of the bags in the bag box broken away.
- 65 Figure 9 is a vertical section of the machine in a fore-and-aft plane.
- 70 Figure 10 is a horizontal section below the table, showing the main or index cam.
- 75 Figure 11 is a vertical section of the hopper parallel to the front of the machine.
- 80 Figure 12 is a detail of the clamping conveyor of the sealing station.
- 85 Figure 13 is a detail of the ratchet drive for the said conveyor.
- 90 Figure 14 is a detail of the chain of the conveyor.
- 95 Figure 15 is a cross section of the conveyor.
- 100 Figure 15-a is a fragmentary view of the conveyor back.
- 105 Figure 16 is a detail vertical section of the closer and scorer.
- 110 Figure 17 is a detail elevation of the closer from the outer side.
- 115 Figure 18 is a formal plan of the bag box connections with the box retracted.
- 120 Figure 19 is a similar view showing a succeeding position of the operative means, the projected position of the parts being dotted.
- 125 Figure 20 is a detail section of the index brake.
- 130 Figure 21 is a similar view of the gluing station.
- 135 Figure 22 is a similar view of the folding station and the ball-and-indent index check device.
- 140 Figure 22-a is a detail of the link from the operating lever to the closer.
- 145 Figure 23 is a detail of one form of cam for operating the opener and conveyor of the sealing station.
- 150 Figure 24 is a detail of an adjustable cam.
- Figure 25 is a cross section of the base part of the last named cam.
- Figure 26 is a detail of a possible form for the cams for the trap reset, the gluing device, and the folder.
- Figure 27 is a diagram of the cycle and angular relations of the actions of the several station mechanisms and other parts in one possible arrangement.
- Figure 28 is a detail plan of the measure and its mounting and operating means.
- Figure 29 is a plan of the index bar detached.
- Figure 30 is a longitudinal section thereof with the index pawl or latch element in place.
- Figure 31 is a cross section on the line 31-31 of Figure 30.
- Figure 32 is a perspective view of the wall of the index bag carrier.
- Figure 33 is a similar view of the base ring for the index bag carrier.
- Figure 34 is a detail top view of the trap parts as removed from Figure 8.
- Figure 35 is a fragmentary section similar to Figure 9, showing a pneumatic throat opener associated with the bag opener 138.
- Figure 36 is a section on the line 36-36 of Figure 35.
- Figure 37 is a fragmentary front elevation of the throat opener.
- This machine is generally of a turret-type, in which a rotating carrier receives a bag and moves it step-by-step, in an orbit, stopping at stations as indicated in Figure 2, where various operations are performed successively to introduce a measured quantity of articles or material into the bag, shape the bag, crease it for closing, apply gum to the flap, press the flap into closed position, then hold the sealed flap clamped for a substantial time, so that the gum will set sufficiently to assure a very secure permanent seal, and finally discharge the filled container. While the index action involves seven steps in 360 degrees, there are but five stations utilized in the present showing, no treatment being effected on the package at two intermissions but one of these may be used for any special treatment desired.
- The invention may be considerably modified in its structure from that specifically illustrated here, without departing from the spirit of the claims as hereinafter presented; but as embodied in this instance it includes a stand of a simple form adapted to afford a maximum clearance and ready accessibility of the under parts of the machine, all of which are at a good level from the floor to avoid spattering of liquids from the floor thereto, as well as to permit ready inspection and servicing from beneath. The stand comprises a single leg 40 of heavy steel tubing, located at the extreme back part of the machine, and provided with a foot 41 of good breadth, extended forwardly so as to afford a safe base for the machine. The upper end of the tube is set in a socket 42 of a knee bracket or lower frame piece 43 which includes a substantially rectangular body plate 44 and upstanding boundary walls or flanges 45. At the right and left sides the walls have upward extensions formed as brackets 46, secured to the under side of a table 47, which, with the knee bracket, constitute the lower principal framing elements of the machine. The socket 42 is a cylindrical sleeve integral with and extending below and also above the plate 44, medially of the rear part of the latter, suitable reinforcing webs joining the two as required.
- The table is formed with a depending bound-

ary flange 48, and is also rectangular, but of greater horizontal dimensions transversely and fore-and-aft. It is spaced above the plate 44 sufficiently to accommodate a main cam and certain other operative parts of the machine within the knee bracket, or on the walls 45, and the table serves as a bed plate for some operative parts. At the sides and rear of the table, posts 49 are erected, carrying a platform 50 which serves for the mounting of the hopper and operative parts associated directly therewith. There is also provided a smaller circular top plate 51 below the platform a distance, serving as a bed plate for the mounting of certain operative parts.

On the extreme left side of the knee bracket a bracket 53 is provided, carrying a conventional electric motor 54 having its shaft parallel to the side of the knee bracket, a belt 55 being engaged on a pulley 56 at the forward end of the motor shaft and extended across the front of the machine to a clutch pulley 57 mounted at the right hand side of the knee bracket. This latter pulley (see Fig. 3) is mounted to slide and idle on the stud end of a horizontal worm shaft 58 by which the entire mechanism is driven, journalled in a small speed reduction case 59 secured to the lower side of the knee bracket. The stud end of the shaft is additionally supported by a roller bearing 60 in a supplemental bracket 61 suspended from the under side of the plate 44. A friction-faced disc 62 is keyed to the shaft next to this bracket, and the pulley 57 has a suitable face to engage the friction disc. The opposite side of the pulley is formed with a hub 63 having an inner anti-friction bearing 64, and an outer anti-friction thrust bearing 65, the latter including a hardened cap plug 66 set in the inner race member thereof. The extremity of the shaft 40 is recessed to accommodate a co-axial helical spring set therein and bearing against the cap plug to yieldingly press the pulley 57 from the friction member 62. The clutch is operated by means of a hand lever 67 fixed on the outer end 45 of a shaft 68 rockingly mounted in a bracket 69 on the front of the knee bracket, and also supported by a hanger bracket 70 on the right hand side of the table 47. A rocking beam 71 is pivoted in a knuckle on the lower part of the bracket 69 below the shaft 68, the lower end of the beam having a bearing screw 72 adjustable therein, arranged to bear on the clutch plug 66. The shaft 68 has a cam 73 fixed thereon in the bracket 69, with a flat face normally opposed to 55 and receiving a flat shoe face on the upper end of the beam 71, and having a higher part at each side so that slight rotation of the cam will bear the shoe outwardly and cause the pulley 57 to be pressed inward, engaging the clutch.

In the case 59 a worm gear 75 is meshed with the worm 74, being fixed on a horizontal shaft 76 journalled in the case and projecting beyond the knee bracket at the outer side, and also extending from the case 59 at the inner side. On the outer end of the shaft an opener cam 147 to be described is fixed, and on the inner end there is a bevel gear 77 meshed with a similar one 78 (1 to 1 ratio) on the lower end of a vertical main shaft 80 supported in an anti-friction bearing 79

70 mounted centrally on the plate 44. This shaft extends upwardly through the table 47 and through a center post 81 mounted on the table 47, the post having a foot flange 82 secured to the table. The post 81 stops short of the platform 50 a distance, to accommodate thereover

certain cams on the shaft 80 to operate station units, as will be described, and for gearing to transmit power from the shaft 80 to units on the platform associated with the hopper, as will be set forth. A bushing 83 is driven onto the post 81 against the flange 82, and has a bottom flange 84 supporting revolvably an index frame 85.

The frame 85 constitutes the principal part of an index table and carrier, for carrying bags from station to station step-by-step. The frame 10 is an annular plate having an upwardly projected hub revolvable around the bushing 83, the plate having a machined brake face 86 on its upper side, part of which is used as a brake face and having seven indentations 87 therein equally spaced circumferentially. Its under side is spaced closely over the table 47 and seven pins 88 are set therein equally spaced in a concentric series, projecting below the level of the table top. To accommodate them for orbital movement 20 horizontally a channel 89 is formed in the table, and means to be described is provided to move the index table step-by-step by engaging and pushing these pins successively. The index frame is provided with a number of radial arms 25 90 inclined slightly upward, and supporting at their extremities a vertical cylindrical sheet metal wall 91 concentric with the post 81 and fixed releasably on the arms 90 for rotative adjustment thereon. This wall is formed with three or more 30 inclined slots 92, each extending from near the lower edge of the wall in a common direction a suitable distance. The slots are utilized for support and adjustment of a horizontal rigid carrier ring 93 having a mounting bolt 94 and pins 35 94' extended through respective slots 92, and the bolt secured releasably to the wall by wing nut 95a.

The ring 93 serves as the support for seven bag carriers 95 to be described, which are uniformly 40 spaced circumferentially thereon and are moved from station to station by the step motion of the index table. The carriers have wings 96 fixed on each side, intended to guide bags into position at the filling station after being filled and released from the bag box and before being gripped on the carrier. The circular, horizontal top plate 51 is of the same radius as the wall 91 and mounted closely thereover, this plate being centrally apertured around the post 81 and having a hub fitted on and removably secured thereon. Beneath the hub of the plate 51 there is engaged and also fixed on the post 81 a brake ring 98, having a series of bosses 99 vertically bored. In one or more of these, friction blocks 100 are 55 mounted at the lower parts, pressed downwardly against the brake face 86 of the index frame by springs 101 confined by adjusting screws 102 engaged in the upper ends of the bores. One or more other bosses have their bores at the same radius 60 as the recesses 87 and positioned so as to align with respective indentations 87 on each step of the index action. A ball 103 is pressed downward in each of these last named bores by a spring 104 confined by a screw 105, so that the 65 ball will yieldingly engage in the indentations successively as each step movement terminates.

The index means

Fixed on the shaft 80 within the knee bracket 70 there is a main horizontal or index cam 106 in the form of a disc having an index cam groove 107 in its upper side, and having a peripheral closer cam face 108. Pivoted on the under side of the table 47 to the left there is a lever 109 75

extending over this cam and having a wiper 110 intermediately positioned thereon engaged in the groove 107, the lever being extended at an oblique angle toward the front from adjacent the wiper, its extremity being formed with a longitudinal slot 111 open on the end of the lever. The lever end will thus oscillate in a fore-and-aft direction when the cam rotates. An index bar 112 is mounted to reciprocate fore-and-aft in a channel on the under side of the table top beside the path of the pins 88, the wall of the channel 89 being cut away to expose the side of the bar in the channel 89 a distance. A pin 113 on the under side of the bar at a medial point in the length of the bar is engaged in the slot 111, so that the bar is reciprocated by the lever 109. On the upper side of the bar a spring-pressed latch or pawl 114 is pivoted at 117, having an index pin-engaging arm 115 to swing laterally from the bar into the path of the pins 88, and being extended at its opposite end beyond its pivot to afford a buttress and stop arm 116, the inward movement of which is checked by a pin 117 set in the bar. A spring 118 is shown to hold the arm 115 yieldingly extended. The top of the bar is recessed to accommodate the pawl 114, and this recess may have a wall 119 concentric with the pivot and receiving the broad end of the arm 116 thereagainst as a buttress to sustain the thrust against the pins 88 when the bar moves forward. The bar 112 is made in sections extensibly connected, so that the termination of index stages may be adjusted without varying the swing of the lever 109. For this purpose the portion of the bar carrying the pawl is slidable on the body part which carries the pin 113, as in Figures 8 and 29-31. Here the bar is cut away at the upper side through the edge next the channel 89, and longitudinally slotted as at 121, and a block 120 set slidably therein, on which the pawl is directly pivoted as before described, the block including the shoulder 119 and a rib 122 extended into the slot 121. The bar has a longitudinal threaded opening leading from its rear end to the slot 121, in which there is engaged a screw 123 swivelled in the block 120 so that the latter may be adjusted longitudinally on the bar by rotation of the screw, a set screw 124 holding the screw 123 at adjusted positions.

50 Bag presenting means

At the front of the machine is the filling station, where a bag box 125 is provided, consisting of a base slide 126 having parallel channels in its under side set over respective rail bars 127 projected horizontally forward from the edge of the table 47, the channels having cover plates enclosing the bars, by which the slide is secured against tilting. On lateral extensions of the base transverse channels are formed, in which are set L shaped bases of uprights 128 secured in relatively adjustable positions by binding nuts and bolts 129. The uprights are vertically slotted and have vertically slidable thereon channelled parts of side plates 130 of the box proper, secured by thumb screws 130' engaged through the slots to clamp the plates to the uprights. Each plate 130 includes a bottom flange inclined downwardly toward the inner part of the machine, being curved upwardly toward their outer front parts, and at the extreme inner vertical edge of each plate there is formed thereon a narrow vertical side flange 131 against which the first bag in the box will set, but permitting the bag to be drawn bodily through the end of the

box by an opener to be described. A pivot pin 132 is provided in the lower side of the base 126, on which a draw link 133 is pivoted, this being extended under the table, offset at its inner end, and connected to the left end of a lever 134 of the first order pivoted on the under side of the table top as in Figures 7, 18 and 19. This lever has an upstanding strike lug, pin or roller 135, mounted at the right end, on its upper side close beneath the forward end of the index bar 112. This part of the bar 112 is provided with two blocks 136-137 on its under side forwardly of the pin 113 and mutually spaced longitudinally thereon less than the length of reciprocation or stroke of the bar, so that when the bar is at its forward limit of movement the block 136 will have engaged the pin 135 and moved the lever 134 so as to cause the bag box to move (or protract it) to its inner limit of travel, as in Figures 7 and 9, and when the bar has been retracted to its rearward limit, the block 137 will have engaged the pin 135 and moved the lever 134 so as to retract the box to the outer limit of its travel.

25 The bag opener

A bag opener is provided, including a bag entering element of conventional form consisting of a planiform sheet metal plate 138 mounted to reciprocate in a vertical plane immediately outward of the plane of the flanges 131 with respect to the index axis, when the bag box is at its inner limit of travel—that is to say, slightly within the box. This plate has a lower arcuate edge adapting it to enter a bag readily and is also formed with side flanges 139 nearly or quite at right angles to the plate, their longitudinal edges being inclined from the plate near its lower end upwardly and inwardly from the plate 138 whereby to press the rear wall of a bag rearwardly and out of the bag box when the opener descends into a first bag in the box. The opener is mounted on a horizontal arm 140 fixed by set screw 140' for adjustment on a vertical reciprocating rod 141 carried slidably in a bearing sleeve or standard 142 the lower end of which is inserted through an opening in the table 47, a foot flange 143 on the sleeve being secured to the top of the table. The rod projects below the sleeve and is connected by a short link 144 to the end of an opener-operating lever 145 located to the right of the knee bracket and extending rearwardly, where it is fulcrummed on a bracket 146 extended downwardly from the rear corner of the knee bracket. An opener cam 147 is fixed on the shaft 16 between the lever 145 and the side of the knee bracket, this cam being a plate with a cam groove 148 therein in which a wiper 149 carried by the lever is engaged. This cam may be formed as formed in Figures 5, 25 and 24, where the cam groove is circular, formed on a thick plate 150 slidably diametrically across the cam body 147, so that at a zero position the cam groove would be concentric with the shaft 16 and no motion at all transmitted, but at the extreme outer position of the plate 150 a maximum reciprocation of the opener will be attained. The plate 150 is fitted in a dovetail slot in the body 147 and may be secured in adjusted positions by screws 151 engaged therethrough from the outer side, bearing against the body 147. The movement of the opener can thus be varied and adapted to the height of various sizes of bags. A longitudinal slot 144 may be formed in the lever 145 to permit ad-

justment of a connection 345 with a link 322 to be described, operating a sealing conveyor. In Figure 23 the cam for the opener is permanently formed with a concentric high part of maximum radius to keep the opener engaged in the bag for a long period, and to effect a quick raising thereof with a short interval for indexing before it descends again, and then a rapid lowering of the opener, so that a maximum of time is permitted for entry of the charge to a bag before the opener is raised. This form of cam groove will not permit adjustment satisfactorily in the construction of Figures 5 and 24, and would require replacement by a differently proportioned cam to accommodate bags differing widely in size.

In the operation of the machine the cams 106 and 147 rotate in unison, but they may be so related that the opener is in lifted position at the time the indexing movement begins by which the index table is moved one step in its rotation, and remains lifted until the indexing movement is completed. However, by reason of the fact that bags are dropped to a lower level than the bag box after filling (in one embodiment of the invention, although not essential) the lifting of the opener is not required to be completed when the index movement begins; but the opener should be at its maximum elevation when the index motion terminates or at least above the level of the throat 204 of the first bag in the box in order to permit the throat to move inwardly of the lower extremity of the plate 138, and past the tongue rest or stop 348 hereinafter described. Should the machine be adjusted or arranged to transfer the bag to the carrier without material drop from the bag box, which may be done with the construction disclosed, the opener cam may be timed so that the opener rise is completed before index motion begins.

In the operation of the apparatus, the material to be packaged is thrown into the bag while the opener is engaged therein, the latter serving in part as a chute to guide the entering material, and after a proper interval the bag box is retracted to its outer limit, thereby releasing the bag, either during or after raising of the opener. The bag then either drops to the bag bottom supporting part of the carrier before the index motion begins, or remains near the level of its position when filled until the gripping or other device of the carrier engages it and moves it, and as a result of, index motion. The carrier ring 93, or the support elements of the carrier receiving the bottom of the bag are so adjusted that the bag is supported on the carrier with its throat above the level of a creaser blade 206 hereinafter described, ordinarily about one inch above the top plate 51, in the actual machine, although this may be varied. Figures 8 and 9 are approximately one-third actual size, and Figure 16 about one-half actual size.

Measuring and filling

A hopper 151 circular in plan is mounted over the platform 50, having a semi-spherical bottom terminating in a circular opening 152 with a short, circumscribing, depending lip 153, set in a collar 154 forming part of a pivoted frame 155 pivoted at the left of the hopper. The swinging end of the frame 155, as seen in Figure 1 is bolted detachably at 156 to an upstanding boss on the platform 50. It should be noted that in the present embodiment the vertical axis of the hopper is spaced forwardly from the axis of the index

table and shaft 80, affording a shorter stroke for the measure to be described, and greater diameter for the hopper. The frame 155 includes a part extending integrally from the collar 154 to the left, and an arm 157 extending upward and curved toward the right beside and behind the hopper, where an opening is cut in the rear wall of the hopper, and a plate 158 on the upper end of the arm 157 is secured to the wall of the hopper at this opening. A bearing 159 is formed centrally of the plate, from which a bearing arm 160 extends horizontally into the hopper slightly below the geometrical center of the semispherical bottom. The arm 160 has revoluble therein an agitator shaft 161, to the inner end of which, short of the vertical axis of the hopper, there is secured a sweep 162 consisting of a central arm 163 extending diagonally to swing in an arc clearing the sides of the opening 152 and in a plane coincident with the vertical axis of the hopper, where an inclined paddle or vane 164 is attached, having an inclination from its lower edge upwardly in one direction so that when the sweep moves in this direction the material engaged by the vane will be pressed or packed downwardly in the opening 152. In addition, the sweep includes horizontal extensions spaced below the arm 160, and from the extremities of these curved agitator arms 165 are extended downwardly so as to be spaced a short distance from the adjacent surfaces of the bottom at all times. With the hopper filled with pulverulent material or granular material, the movement of this sweep over a short radius will keep the stock in a flowing state, and cause it to readily feed into the mouth of the hopper beneath the vane 164.

On the outer end of the shaft 161 there is fixed a crank arm 166 to which a link 167 is connected detachably by a removable pin 167', and pivoted on an eccentric 168 of a short horizontal shaft 169 mounted in a bracket bearing 170 which forms a bridge over a measure slide and a measure operating crank arm, to be described. The shaft 169 is driven by 1-to-1 bevel gears 171 from a vertical counter shaft 172 mounted in a bearing 173 set in the platform 50. The counter shaft 172 is driven in synchrony with the main shaft 80 by two sets of bevel gears 174 and 175 and connecting horizontal shaft 176 journaled in brackets on the under side of the platform.

The platform has a rearwardly extending guide channel 177 formed or constructed on its upper side in the medial line of which the bearing 173 is mounted, and reciprocable in the channel there is a measure slide 178 which is in the form of two parallel side bars 179 spaced apart to move freely on each side of the bearing 173 and connected at their forward and rear ends. Each has an upwardly offset forward extension 180 between which there extends a cross bar 181. To these extensions the side walls of a measure box 182 are riveted. The box consists of two side walls 183 and a front wall 184 formed from a strip of sheet metal bent at right angles at the lateral limits of the front wall 184, substantially in a U-shape. Snugly 185 slidably between the side walls of the box there is a back wall 185 having a planiform top plate 186 flush with the top edges of the box, and provided with a downward extension 187 at its rear extremity, in which an adjusting screw 188 is swivelled, threaded in the cross bar 181, by which the rear wall may be adjusted to vary the capacity of the measure. The top of the box is spaced a distance below the lip 153 of the hopper, and in the lower side of the

hopper collar 184 there is formed a fore-and-aft channel 189 (Figure 11) much wider than the measure box, and having opposed horizontal grooves in its sides immediately below the lip of the hopper, or at least at the plane where the opening from the hopper through the collar terminates. In the grooves there is set a removable planiform discharge plate 190 serving as the bottom of the hopper and having a rectangular opening therethrough of a width slightly less than that of the measure box, and having its forward edge positioned to aline with the wall 184 when the measure is retracted to loading position, while the rear edge of the opening may be located to aline with the rear wall of the measure at the same time, if the measure is enlarged to its full capacity by rearward adjustment of the wall 185. The lower edges of the measure are slightly above the top level of the platform 50, and adjacent the mouth of the hopper the platform is formed with a slot 191 of a width somewhat less than that of the channel 189, and extending forwardly from a point rearwardly of the discharge plate 190 and opening through the front edge of the platform, which front edge is set back from that of the table 41. Along each side of this slot 191 the platform 50 has slightly raised bosses on which a measure bottom plate 192 is secured, fitting snugly the lower edges of the measure when the latter is set properly in close relation to the discharge plate 190. This bottom plate stops short of the rear end of the slot 191, so that material leaking or working out from the measure may drop over its rear edge when pushed back by the wall 185 on retraction, and a fender plate 193 is mounted thereunder, to catch such material, its rear edge being flush with the platform at the rear end of the slot 191, the plate being inclined downwardly and forwardly over and beyond the gears 175, so as to permit waste material to slide on the plate and drop into a waste chute associated with a trap to be described. The manner of mounting the bottom plate facilitates its dissipation of heat, and the measure being free of guide walls at the side is likewise free of heating tendencies found in many prior machines from that cause.

In this way also the accumulation of waste stock within the machine is minimized, and wear and damage of the operative parts by access of such material also reduced to a notable minimum.

Secured to the front edge of the platform 50 in line with the measure there is a tunnel device 194 of sheet metal, rectangular in cross section, its rear wall being cut away at the upper part and extended slightly under the bottom plate 192, its side walls receiving therebetween the measure when moved to its forward limit. The opening in the tunnel is adapted to accommodate the maximum fore-and-aft dimension of the measure, and its rear wall is inclined forwardly and downwardly so that its end will lie close above and forwardly of the rear wall of a bag when the opener is engaged therein. The tunnel lies between the side flanges 139 of the opener at all times so that any material dropping from the measure into the tunnel will be guided into the bag.

The measure is operated by means of an arm 195 fixed on the shaft 172, spaced above and swinging over the slide 178. On the extremity of the arm a depending hardened wiper pin 196 is mounted lying very closely over the slide at respective limits of the orbit of the pin. The slide is provided with respective strike blocks 197 and 198, on the left and right side bars of the slide, the

one located further to the rear than the other on the slide, and the inner ends of these blocks are also spaced from the medial vertical plane of the slide so that the pin 196 will engage one and after moving the slide to one limit will clear the block and swing over a substantial arc before engaging the other block and returning the slide to the opposite limit of its movement. Thus the measure is given a considerable period of rest both at loading and in discharge positions, although the loading begins before it reaches this rest position and continues as it departs toward discharge position, and discharge begins before the full advanced position is attained as well as in its initial return movement. The distance from the forward edge of the discharge opening in the discharge plate to the front edge of the bottom plate is such that the measure is closed under the hopper before it projects over the edge of the bottom plate when the measure is adjusted to its largest size, which obviates the possibility of an excess charge being delivered in case of slow motion of the machine.

The rotation of the arm 195 may be timed so that it engages the block 198 and begins to move the measure forward while the opener is being lowered into the bag, and the front wall of the measure may pass beyond the bottom plate 192 before the opener is fully lowered, as the bag will have been opened to the maximum before the opener is fully lowered. And the retraction of the measure may begin before the opener begins to rise, especially if the opener is operated by the cam of Figure 23.

The sweep in the hopper is also timed to swing in the direction of its upward inclination while the measure is at loading position beneath the opening of the discharge plate, preferably passing partly or completely over the opening before the measure starts forward.

The bag

While my invention is adaptable to use with various receptacles and containers, in its present form it is especially adapted to use with what are termed flat bags, but which are also known in other arts as envelopes. Each bag 200 has a front wall 201, a back wall 202 joined to the front wall at both sides and bottom only, the bag being oblong with its open edge at one end ordinarily. The front wall has an integral tongue 203 extending upwardly from the level of the top edge of the back wall, with a uniform or nearly uniform width equal to that of the envelope for a distance above the throat 204 which is the top edge of the back wall. As initially manufactured and supplied to the bag box 125, no crease or score is formed at the base of the tongue, so that the bag face and tongue are one flat piece.

Closing and scoring station

At the next sector of the machine beyond the filling station in the direction of index movement, is the closing and scoring or creasing station. As a means for retaining the filled bag in its proper path a top guide rail 205 is provided near the level of the base of the tongue of the filled bag when dropped to the carrier. The top guide rail 205 would preferably be inclined downward to a lower level immediately following the closer station. This rail may be continued past as many stations as desired, although it may be interrupted and lowered, as will be described. At its beginning next the bag box, it is located outwardly of the normal path of the advancing vertical edge of the filled bag when advanced by the

rotation of the carrier and following wing 96. The rail is preferably above this wing, and is inclined inwardly toward the closer station so as to insure movement of the top of the bag within the closer device.

At the closer station (see Figs. 16-17 and Figs. 8-9 and 10), a rectangular angle piece 207 is secured to the top plate 51 with one vertical flange projecting upward at the outer side as an anvil, being at right angles to the medial radius of the station, and flush with the periphery of the wall 91 and plate 51 and its ends consequently projecting outward at a tangent to the wall 91. A small guide plate 208 (see Fig. 8) is riveted to the upper side of the top plate, inclined outward from the periphery of the plate 51 to the adjacent end of the outer face of the anvil 207. The upper edge of the anvil is bevelled and a rectilinear creaser blade 206 is fixed on the bevel, projecting outwardly from the piece 207 a short distance.

A hinge bracket 209 is mounted on the under side of the table 47 having knuckle ears at its outer end between which is pivoted an arm or lever 210 which extends upwardly through a slot 211 in the table edge and outwardly of the carrier ring 93. The lever has a heel portion at its lower end projecting outwardly from the pivot of the lever and having a contractile spring 212 connected thereto extending downwardly and anchored to a pin on the front of the knee bracket, to keep the lever yieldingly inclined outwardly as dotted in Figure 16. The bracket 209 also has a channel on its lower face with undercut sides in which a slide 213 is engaged, connected by a short link 214 to an arm 215 on the lever 210 below its pivot, and on the slide at its lower side a wiper 216 is mounted bearing against the peripheral face cam 108 of the main cam 106 by action of the spring 212. The guide portion of the bracket 209 is fastened to a boss 217 formed on the under side of the table, extending across the bottom of the channel 89 over the main cam 106 and also having a threaded opening at one side of the slide channel receiving the pivot screw 218 (see Fig. 10) by which the index lever 109 is mounted on the under side of the table close beside this slide 213 (see Fig. 9).

The upper end of the lever 210 is formed with a bracket plate 224 at right angles to the lever, channelled on the radius of the station, and secured thereon by a bolt 225 adjustably is the ribbed foot piece 226 of a cross head 219 parallel to the anvil. This is formed with a deep horizontal channel throughout its length at the inner side, in which there is set a soft rubber or other suitable block or cushion 220, projecting from the channel toward the anvil 207, and positioned to receive the blade 206 therein when the lever operates. A thin leaf spring 221 has one end fixed on the upper part of the foot piece 226, projecting downwardly and broadened and adapted to engage the outer side of a filled bag on the carrier at the station when the lever is moved inward, the lower part of the spring thus serving as a presser plate 222. The base 223 of the spring is projected inwardly from the point of attachment to the foot piece abruptly, and at a suitable distance from its mounting bent downward at a line so located that it will be above the material in the bag, or above the major part of such material. When the spring engages a filled bag at the station, the base portion is pressed inward while the lower part of the spring yields, thus effecting a working of the content 75 of the bag to distribute the material for better

shaping of the package. The plate portion 222 may be variously shaped as desired for its function.

When the lever 210 swings inward, it presses the interposed upper end portion of the bag against the sharp front edge of the blade 206, forming a score or crease at the line where the fold is to occur when the bag is sealed. By reason of the adjustment of the carrier to hold the throat of the bag above the blade, both walls of the bag are creased and become folded down in the subsequent folding operation. The spring plate 222 is held yieldingly in an initial position with its extremity spaced from the path of the bag when the lever 210 is retracted to its outer limit of movement.

The rise of the cam 108 may engage the wiper 216 shortly before completion of the index movement if desired, and may have a high part of considerable length and concentric with the shaft 80, or may be undulated as in Figure 10 over this high part, to produce a repeated working action by the spring 221 against the bag, by which the charge therein will be caused to settle in the lower corners and to the sides of the bag, and a better forming of the package attained. The high face of the cam may terminate at the wiper 216 any time before, or about, the time the succeeding index action begins.

Following the closing and scoring station, the bag will have a stop at the termination of the index action, where, as disclosed, no treatment of the bag is effected. But this may be utilized if desired by provision of any approved treatment devices or mechanism available for use with the machine disclosed. This may be termed an idle station herein.

The gluing station

The gluing station, located at the second step 40 or station from the closing and scoring station (see Figures 8 and 21), includes a guide piece 250 in two pieces, including an upper horizontal platen plate 251 advanced beyond the station at its receiving side and provided with a hub 252 45 set revolubly on a pin 253 fixed vertically in the extremity of a bracket 254 extended from the adjacent side post 49. This hub is secured by a set screw 255 engaging the pin 253.

The platen plate is considerably elongated, so as to extend entirely over the upper end of a bag and beyond, and has formed therethrough a longitudinal slot 256 under which the tongue of a filled bag may lie while a glue bar is pressed upward against the tongue. The platen is suitably reinforced by a stiffening rib at the upper side and has two longitudinally spaced transverse slots 257 therethrough, around which the rib is enlarged; and engaged through these slots there are respective clamp screws 258 engaged in an outward top flange of a planiform vertical guide plate 259 set and held by the screws against the under side of the platen outwardly of the slot 256 and parallel thereto. It is adjustable relatively to the slot 256 by means of the screws 258. 65 Comparatively slight adjustment of the slot 256 radially of the station will be required, and this may be attained by a slight degree of rotation of the platen on the pin 253 after loosening the screw 255.

A wide slot 260 is formed through the top plate 51 from its periphery at the gluing station, and set in this there is a glue pot or box 261, rectangular in plan and of a width at least equal to the greatest length of area of adhesive required to be 75

- applied to bags in this machine. The box has its upper edges slightly below the level of the platen 251 and well above the plate 51. The front side 262 of the box is inclined outwardly from the bottom to the top of the box, and this may be extended outwardly of the wall 91. This front wall of the box may have attached to its upper edge a lip plate 263 inclined upward and outward a short distance further, where it is bent to lie nearly or quite horizontal and provided with a guide edge 264, to lie close to the guide plate 259, so that the part of the bag over the crease 265 will engage over the lip and be caused to project inwardly beyond the front edge of the pot and under the platen slot in the path of a glue bar to be described, while the two lower wall portions pass between the lip 263 and plate 259.
- The glue pot has a mounting bracket or flange 266 on at least one side having an elongated slot 267 parallel to the radius of the station through which slot a clamp screw 268 is engaged in the top plate 51 to support the pot and also permit its adjustment inward and outward for long and short tongues of bags, although the variation in length of tongues is slight in different sizes of bags, and such adjustment will not be great. To assure proper entry of the bag edge between the lip plate 263 and plate 259, a small fender plate 269 may be secured on the top plate 51 in advance of the glue station.
- A bracket 270 is mounted on the under side of the platform 50 beside the medial radius of the glue station, extending downwardly to a proper level and having pivoted thereon a bell lever 271 having a depending wiper arm 272 formed with a ball head 273 resting against the periphery of a horizontal disc cam 274 formed on the same piece with the cam 242 (hereafter described) on the main shaft 80. The lever has an arm 275 extending downwardly over the glue pot and an outer section 276 pivoted thereon to swing relatively to the arm in its plane of oscillation, for adjustment of the outer part upwardly and downwardly thereon, and secured in adjusted positions by a clamp screw 277 engaged through a slot in the section 276 and screwed into the arm 275. The outer end of the section 276 is offset downwardly so as to enter deeply into the glue pot, and has fixed thereon a transverse glue bar or blade 278 in the form of a simple planiform plate with an upper horizontal rectilinear edge projected above the adjacent portion of the lever section 276 so that it may press against a bag flap or tongue properly when raised. The glue blade 278 in the form of a simple planiform plate various forms of bag tongues. The stroke of the lever under operation of the cam 274 is such that the blade will move from the lower part of the pot upwardly and present its top edge within the slot 260 slightly above the plane of the lower face of the platen 251. The cam 274 may be so positioned and formed as to lift and return the glue blades at any time or over any period during intermission of rotation of the index table, and initial and terminal movements of the bar may respectively be effected during terminal or initial indexing movements if necessary.
- While the top guide rail 205 is not needed throughout the gluing station it is for convenience continued therethrough to the folding station. This top guide rail serves to assist in smooth movement of the bag from the closing and scoring station into initial engagement with the guide plate 259, and on departure aids in locating the top of the bag in the folder to be described.

The folding station

At the folder station a standard 279 is erected, radially adjustable for a purpose to be disclosed. To attain this adjustment the base of the standard is formed with a horizontal foot flange 280 in the under side of which a channel is formed fitted over a guide rib 281 attached to the top of the table 47. The standard has a central vertical stiffening rib at its outer side and on each side of this clamp screws 282 are engaged in the table 10 through slots in the foot flange parallel to the rib 281.

At the top of the standard 279 a transverse horizontal anvil piece 283 extending at right angles to the medial radius of the station is bolted 15 to a suitable boss on the standard having inner and top faces machine-finished to receive corresponding faces on the anvil. The anvil has at its ends respective inwardly projecting ears 284 having therein coaxial conical bearing screws the inner ends of which are set in sockets formed at the ends of a folder 285 the outer planiform face of which is smoothly finished to come into close parallel relation to the inner vertical planiform side of the anvil. A thin facing 286 of rubber 25 or other suitable cushion material is secured to the face of the anvil between the ears 284. The face of the anvil extends below the ears 284 nearly or quite an inch in the operative machine and may be more or less in height as circumstances 30 require, and the folder face is of corresponding area. The facing 286 has been made of moderately soft rubber, one-eighth of an inch thick, the purpose being to secure a good compression of the full area of the folded parts of the bag, and to 35 assure good compression in this way notwithstanding some wear in the folder bearings before adjustment is made. The folder 285 is made with a central knuckle 287 projecting from its back side to which a link 288 is pivoted centrally of the folder 285, extending upwardly to the outer end of a long arm of an operating lever 289 pivoted on a bracket 290 secured on the top plate 51, an inner short arm of the lever 40 extending over the glue cam and a crown cam 45 291 formed integrally on the top side of the glue cam concentric with the shaft 80. The inner part of the lever and the bracket are offset laterally from the outer part of the lever and away from the adjacent glue pot and depending bracket 50 270. The inner arm of the lever is provided with a ball wiper head 292. The offset of the lever affords this ball ample clearance for its movement without interference with the gear 114 immediately thereabove on the shaft 80. The 55 lever 289 is held yieldingly in raised position by a contractile spring 293 suspended from the platform 50. The upward movement of the lever is sufficient to swing the folder 285 inward from the anvil and upward to approximately open position, 60 by action of the spring, putting the folder on a level with the platen 251 and leaving ample clearance for the upper end of a bag from the glue station to move under the folder with the tongue close under the folder. For the guidance 65 of the bag properly in this respect, the top rail 205 extending from the point where it is shown in Figure 21 will lie inwardly of the end of the anvil facing 286 so as to insure the movement of the advancing side edge of a bag inwardly of the 70 anvil 283. The rail 205 may be interrupted and stopped short of the anvil, so as to not deform the bag as the folder presses it outward against the anvil, or may be lowered and carried below the anvil a distance. The bag leaving the glue sta- 75

tion will have its tongue held downward by the platen 251 and the end of the platen 251 next the folding station may be provided with a tongue 294 inclined downwardly slightly so that any 5 tendency for the tongue of a bag departing from the glue station to spring upward and strike the end of the folder will be counteracted and the tongue pressed below the folder 285. In addition, for proper placement of the entering bag for 10 folding at this station, a guide plate 295 may be mounted on the top plate 51 to engage the part of the bag below the scorer and press the bag toward, but not against, the platen after passing the rail 205. As the folder descends upon the 15 bag tongue, by the resilience of the paper reacting against it the paper itself will press the bag snugly against the anvil so that folding will occur properly. The glue coated surface is thus pressed against the side of the bag below the crease and 20 held long enough to be retained after the folder rises again.

Little adjustment of this device will be required to accommodate paper of various thicknesses, but provision is made for ample adjustment 25 for this purpose and additionally to compensate for wear or varying thickness of facing on the anvil either by aging or incident to replacements. The length of the lever and link in the folder, as well as the pivotal connections 30 and wiper bearing are permanent, and the clamping action is regulated by radial adjustment of the standard 279. Movement of the standard outward permits lighter pressure, and by reason of the inclination of the link outward in its lower 35 part, movement of the standard inward will effect further closure of the folder on the anvil, either movement being attained by loosening the screws 282 and pressing the standard in the desired direction. In order for this adjustment to 40 be effective, it is necessary that the link 288 have an outward inclination toward its lower end when the folder is in closed position—that is, the projected geometrical arc described by the pivot center at the lower end of the link 288 around 45 the pivot center on the lever 289 while the latter is lowered to the maximum, must pass substantially below the pivot center of the knuckle 287 when the folder is in closed position. The link 288 is a longitudinally resilient element, which 50 will tend to yield to longitudinal compression between the lever 289 and knuckle 287, so that it may be of an excess length, and thereby automatically compensate for wear, diminished resilience of the facing 286 and irregularities in the 55 thickness paper, and other accommodations. This link is in the form of a serpentine spring formed from a flat band metal, having its extremities bent to provide eyes 288' to receive pins for its pivotal mounting on the lever and 60 the folder 285.

The sealing station

At the right hand side of the table 47 there is 65 erected a standard 296 and on the post 49 a bracket 297 is secured, the former being nearer the back of the machine and being nearly or quite vertical while the latter is inclined outward so that its extremity is on a line with the standard 296 at right angles to the medial radius of the 70 sealing station. The standard has a bearing 298 on the line mentioned in which a main conveyor shaft 299 is mounted. A conveyor 300 is mounted on the standards, a middle drive sprocket 303 of which is fixed on the shaft 298 and end sprockets 301 of which at a lower level are carried at

the ends of respective frame bars 302 mounted for longitudinal adjustment on the standard, so that the conveyor may be kept taut or adjustment of the gap made, as will be understood. Side rails 314 are mounted on the standard and bracket 5 at each side of the lower reach of the conveyor, upon which this part of the conveyor is supported throughout its length. The conveyor comprises a link chain 304 comprising blocks 305 and links 306 all of which may be stamped from sheet metal, as shown. The blocks comprise two identical parts L-shaped in section transverse to the chain and consisting of an inner plate 307 forming one-half of a block, to which a similar plate 10 is laid in registry to form the other half of the block. Each plate 307 is apertured at each end 15 to receive link pins 308, and has an outer mounting flange 309 extending at right angles to the plate in a plane parallel to a line from center to center of the apertures in the plate. The flanges 20 thus extend oppositely from each other and are riveted or welded to clamping members to be described. The links comprise a pair of similar plates and flanges but instead of the plate portions being close together, they are spaced to receive the block portions therebetween. The flanges of the link members are also riveted or 25 welded to clamping members coacting with those carried by the blocks, as will be described. The teeth of the sprockets fit between the pins 308 30 and plates 307 of the blocks.

The clamping members of the conveyor are alternate rigid elements 310 and elastic cushion elements 311. The rigid element consists of a simple rectilinear bar or tube 312 rectilinear in 35 cross section arranged transversely of the chain with a planiform face 312' at the lower side to which are secured one pair of flanges 309 of the chain. The bars may be variously formed but as illustrated may comprise lengths of rolled or 40 drawn tube stock. Their cross sectional dimension is greater in a direction perpendicular to the planes of the flanges 309. Each cushion element comprises a top plate 313 of hard metal extending parallel to the bars 312, but of greater 45 length so as to project at each side of the conveyor over the parallel rectilinear rails 314, one rail being carried by the bracket 297 and the other by the standard 296. A back wall 315 which may be integral with the plate 313 is extended outwardly from one longitudinal edge of 50 this plate at right angles, on which an outer retaining wall or flange 316 is formed at right angles, making a channel-like space between the plate 313 and flange 316, in which there is 55 secured a block 317 of cushion rubber of the same length as the bar 312, and having a face abutting and compressed by one adjacent bar 312 when the chain is arranged in a rectilinear path. The area of this compressed face of the block may 60 be the same or less than that of the abutting face of the bar, but is sufficient to cover an area equal to that of the folded end part of the bag. The thickness of the rubber blocks and the bars is such that when the chain and clamping members are arranged in a rectilinear path the aggregate thickness of all, longitudinally of the conveyor, tends to be greater than the actual length within which they are disposed, so that the rubber is necessarily deformed by compression between the bars. The flange 316 may project from the wall 315 less than the width of the top of the bar 313 and the top of the bar 312 may be arranged lower than the flange 316. The sprockets 301 are a distance below the level of the drive 75

sprocket 303, so that the drive sprocket may clear the lower reach of the conveyor. The plates 313 and flanges 318 are narrower than the corresponding faces of the blocks 317 so that there is no interference with compression of the rubber, and no other element prevents arrangement of the conveyor in a rectilinear path at its lower part with the blocks 317 properly compressed.

The conveyor members 310 and 311 become widely divergent when passing around the sprockets 301 at the ends of the frame, and the operating means for the conveyor moves it step by step so that a gap 321 is formed between two divergent clamping members where the rubber face is exposed at one side, positioned over the carrier ring 93 conveniently to receive a bag top moving forward on the index table. The means for operating the conveyor includes a link 322 connected to the opener lever 145, extended upwardly beside the standard 296 and connected to a ratchet lever 323 pivoted on the main shaft 299 of the conveyor. Fixed on the shaft 299 beside the lever 323 there is a ratchet wheel 324, the lever being projected beyond the ratchet wheel opposite the link 322 and provided with a spring-pressed dog 325, while on the side of the standard spaced from the full stroke position of the dog there is a spring-pressed pawl 326 to hold the ratchet against reverse movement. To simplify the construction, the ratchet is formed with the same number of teeth as the driving sprocket. In this way, one bar 312 and one block 317 will be moved past the receiving position on each operation of the ratchet.

At the receiving side of the sealing station the top guide rail 205 should stop short of the path of the bags in the conveyor. A guide plate 327 on the top plate 51 acts with the rail 205 to confine the advancing bag tops to the path necessary to enter the gap 321 in the open part of the conveyor freely.

The operation of the conveyor to move the two divergent clamp members forming the receiving gap 321 outward until they are pressed together may be coincident with the operation of the opener, and may begin shortly before the index movement of the index table stops, as the advancing bag will have already been entered partly in the gap and actual clamping or material friction will not occur in the early part of the movement of the conveyor. The motion may be otherwise timed, however, as found desirable.

In the operation of the conveyor, it will be noted that the sealed bags are held therein over a period which may be any multiple of the index periods according to the length of the conveyor, and with a comparatively short conveyor, as illustrated, each bag is held clamped therein during two turns of the index carrier of the machine, or fourteen filling operations.

It is also an advantage of this machine that the packages are delivered in an orderly fashion so that they may be readily arranged in cartons or other shipping and sales containers and cases.

65 The carrier

For holding bags in place on the index table, a series of carriers 95 are provided as before mentioned, each consisting of a bracket casting 227 having a back flange 228 secured against the under side of the ring 93 by bolts 229, and having an upstanding front arm portion 230, on which a back plate 231 is secured, extending upwardly and inclined inwardly to the wall 91 near the upper vertical edge of the latter. Two rest or shelf

pins 232 are set removably in one of respective vertical series of holes in the bracket, projecting forwardly to receive the bottom edge of a bag and support the same as a shelf while it lies against the back plate. The pins are thereby adjustable to different levels on the carrier. The back plate has two integral wings 96 before referred to, turned forward from respective sides at the upper part, to steady and retain the bag until engaged by a gripper device on the carrier unit. At the lower side of the bracket depending knuckle ears 233 are formed thereon between which is pivoted a gripper lever 234 having an upper grip arm carrying at each side soft rubber pincher knobs 235 adapted to press upon the lower part of a bag at each side, and a lower wiper arm on which there is mounted a wiper roller 236 on an axis nearly or quite radial to the pivot of the lever. Around the pintle of the lever there is engaged a torsion spring 237 having respective arms engaged with one ear 233 and the upper arm of the lever 234 whereby to press the knobs 235 yielding toward the plate 231. A cam track 238 (see Figs. 8 and 9) is mounted by suitable upstanding brackets 239 on the table 47, immediately adjacent the index table, extending from the sealing station to the filling station. It is concentric with the index table except at the ends where it is curved outwardly (as at 240, Fig. 9) and is so located as to engage and hold the roller 236 pressed inwardly to a sufficient distance to hold the lever 234 and its knobs in the desired open or releasing position. Adjustment of these carriers to accommodate bags more or less deep, is effected by loosening the nut 95' and rotating the ring 93 on the wall 91. Movement of the pins 94' and bolt 94 in the slots 92 causes upward or downward movement of the ring 93, according to the direction of rotation of the ring on the wall 91. Displacement of the carriers from proper station positions on the index table is compensated for by making the wall 91 revolute on the arms 90, and securing this wall adjustably on these arms by means of screws 24 engaged through horizontal slots 242 in the lower part of the wall, and engaged in the ends of the arms 90. These arm ends are formed with shoulders 243 on which the lower edge of the wall 91 rests slidably, so that the wall may be readily rotated without difficulty and without displacement from proper elevation and alignment with the index table. The outturned ends 240 of the track 238 are so inclined that the engagement of the gripper with a bag will not be abrupt, nor tend to damage the paper or contents, nor produce objectionable permanent indentations in the paper and the release movement is effected without undue shock or consumption of power.

Accommodation to different bag lengths may also be effected by adjusting the pins 232 up or down.

Various forms of carrier may be used suited to various containers and materials, and including pneumatic or other holding means if necessary, in accordance with approved practices.

65 The trap

At the filling station, a trap chute 328 is provided (see Figs. 8, 9 and 34) on a swinging support so that it normally presses forward to engage the back wall of the first bag in the box, and in this position, as shown in Figure 9, if a charge should be delivered from the measure while no bag is open, the chute would divert this charge inward into a chute 329 mounted in a suitable opening in the top plate 97, the lower end of the

chute 329 stopping above the level of the arms 90 of the index table frame and discharging the received material between the arms just within the wall 91 into a chute 330 mounted in the table 47, this chute extending forwardly over the front side of the knee bracket and stopping just in front of the knee bracket, where a drawer receptacle 331 is mounted to receive from the last named chute. The drawer is manually removable for collection of the material therein. The plate 193 under the hopper will also discharge material thereover into the chute 329, so that the waste is collected at the same point of collection. The trap chute is a simple sheet metal form consisting only of two parallel walls and an inclined wall joining them and extending from their forward upper parts to their rearward lower parts, where it extends partly into the chute 329. The side walls of the latter are extended upward beside the chute 328 to safely confine material passing downwardly from the latter.

One side wall of the trap chute is riveted fixedly to a pin or arm 334 extending at right angles therefrom, being an extension of a lever 332 pivoted on a foot piece 333 secured to the top of the table to the left of the bag box and spring pressed to remain yieldingly at its outer limit, yieldable to pressure of the front of a bag against the trap 328. The lever is provided with the lateral pin 334 beside the trap above the top plate 51, while to the left of the chute 329 and back thereof a weighted keeper lever 335 is pivoted at near the same level as the pin, on a bracket 336 mounted on the top plate 51. The forward end of the keeper is adapted to swing up and down over the pin, and is formed with a shoe 337 having a flat lower face positioned to rest on the pin when the trap is at the forward limit of its movement, this face being then substantially horizontal. This shoe face is of sufficient extent to permit some movement of the trap inward and outward while the shoe is so resting. At the inner limit of the shoe face, there is an upwardly and rearwardly inclined face 338 adapted to receive and wipe against the pin when the trap is moved a proper distance by an opened bag, so that the shoe may drop in front of the pin, and by action of the weight of the shoe and lever, this inclined face will then press the pin rearwardly still further, drawing the trap chute entirely away from the bag a short distance. The weight will retain the trap retracted until the weight is lifted, which is accomplished by the cam 242, although any other connection may be utilized as found most desirable. For the present instance, an arm 339 is projected downwardly, then horizontally and laterally from the lever 335 and in front of the cam 242, as a simple horizontal rectilinear bar 340. When the lever 336 is lowered this bar is on a level with the lower body of the cam and close to the low face (or part of minimum radius) of the cam, which it clears. The lobe of the cam, however, engages the bar and presses it forwardly, which raises the lever 335. The bar 340 being also raised, the lobe of the cam is increased in vertical dimension at the maximum radius of the cam so as to continue bearing upon the bar 340. When the lever 335 is raised and the shoe 337 clears the pin 334, the spring 341 at the base of the trap-carrying lever 332 swings this lever forwardly again, bringing the upper edge of the chute against the first bag in the bag box and just outward of the forward lower edge of the tunnel 194. This is the initial position. A bar 343 on the chute 328 holds

the latter out of the path of the opener by engaging the inner side of the chute 194.

It is an advantage of the machine that motions of the several station parts may be variously timed within the intermission of index motion, and the timing may be varied from that before indicated as discretion may dictate.

In order to avoid a peak on the motor comprising an aggregate of the major power consuming operations required at the several stations, I am able to take advantage of this possibility of varying the timing, and by arranging the high parts of the several cams in suitable angular relations in the cycle, it is possible to so average the load that a considerable economy of power is effected over that which would be required if the operations such as lifting of the opener, closing of the closer, engagement of the score blade and folder, and step motion of the conveyor all occurred in synchrony. In Figure 27 I have therefore indicated how the cams may be arranged in relation to the cycle of the machine, so that the peak points in the operation of the several stations have been distributed, although as explained, this may be differently arranged with similar effect following the same principle of invention. By this means I have used a one-sixth horse-power electric motor with an ample margin of power, operating at a capacity of 4,000 packets per hour; and it is possible that an even lower power of motor would be sufficient.

Operation

In the operation of this machine, after closing of the circuit to the motor, the hand control lever 67 is moved to bring the flat of the cam 73 against the shoe of the beam 71. The main vertical shaft 80, vertical counter shaft 172, and the short shaft 179 then rotate in unison, until the lever is moved to release the clutch. The main cam 106 on the shaft 80 oscillates the lever 109 and the latter engaging the pin on the lower side of the bar 112 reciprocates the latter, moving it forwardly and after a period of rest at this forward position returning it to initial position. In the forward movement of the bar, the spring pressed pawl 114 engages one pin 88 on the under side of the index frame and moves it quickly one step clockwise as viewed from above. At this time the opener is completing its terminal rising movement. The brake shoes on the brake frame prevent the index frame from rotating too far by momentum, and the ball 103 and indents 87 serve to stop the index table accurately at definite positions at the termination of each index movement. The bar 112 near the end of its forward movement operates the lever 134 and linkage to the bag box to draw the latter inward or rearwardly so that the inner side of the tongue of the first bag is pressed against the lower extremity of the opener 138. The throat of the bag is thus caused by the resilience of the bags next behind to project inwardly of the lower extremity of the opener, so that the latter may readily enter this first bag when moved downwardly. The opener 147 is adapted to move the opener downward at this time. The opener upon entering the bag presses the throat rearwardly against the trap, and the shoe face 337 passes in front of the pin 334, drawing the trap away toward the rear, relieving the rear wall and throat of the bag of all impedance to opening movement. The measure 182 having started forward previously, just after the sweep 62 passed there-

over by which the stock in the hopper is pressed or packed downward into the measure, will now be in full discharge position and the charge therefrom will drain through the tunnel 194 to the bag. After a period of rest of both opener and measure, the two are retracted, the sweep having completed its return swing. Before the opener is lifted, the bag box 125 is retracted, and the opener being much narrower than the width of the bag, the friction between the bag and opener after pressure of the following bags in the box is removed, being insufficient to support the bag and its charge, the filled bag slides off the opener and drops to the pins 232 between the wings 96 of the carrier 95. The opener will still be partly engaged in the bag and its rising movement begins immediately or slightly before, as its initial movement is immaterial. This movement is rapidly completed by accelerated movement, and index action of the machine may begin shortly before the lifting of the opener is completed, but after it has cleared the bag on the carrier ring. The return or rearward projection of the bag toward the opener may begin as the opener nears its upper limit, and the bag tongues are pressed against the extremity of the opener after the latter has reached its full raised position. This means that the main cam has then returned the lever 109 and bar 112 to initial position and that the pawl 114 is in position to engage the next pin 88 of the index frame for the next operation. This index action begins shortly after. The wing 96 on the carrier wall 91 engages the edge of the filled bag if for any reason the bag lags. Ordinarily, however, the bag will be carried forward to the next station without being pushed by the wing.

The closer and creaser arm 210 begins its inward swing by operation of the face 108 of the cam 106 shortly after completion of the index movement which brings the filled bag to the station, and as the lower edge portion of the presser plate 222 engages the lower and somewhat bulged part of the bag, the spring 221 yields, and its upper base portion 223 continues inward and presses the upper part of the back and front walls of the bag close to the anvil 207. If undulations are formed in the high part of the face 108, the plate 222 will alternately relieve and press upon the bag several times, so as to work the charge toward the edges of the bag, and will be withdrawn as the low part of the cam face 108 allows retraction of the arm 210 by its spring.

As the bag is moved to the station, the fender plate 208 assures its free passage outward of the end of the score blade 206 and thereafter the cam 108 moves the block 220 inward. After the spring 221 presses the bag against the plate 222 it yields while the block 220 engages against the side of the bag below the throat, pressing the walls of the bag hard against the blade 206. As soon as the high part of the cam 108 passes the wiper 216 the spring 212 draws the arm 210 outward and the block 220 clears the scored line on the bag, so that the latter may be moved to the next or glue station. The end portion of the bag above the score line may be termed the top flap 341.

On the next index action the bag stops at the vacant or idle station at the left hand side of the machine, where it remains unaltered. The succeeding index action carries this bag under the platen plate 251, with the tongue and wall portions of the bag outwardly of the score line and forming the flap 341 lying close below the platen 251. The platen being above the score line, and

the receiving edge of the platen being inclined from the outside inwardly across the path of the advancing edge of the bag at an acute angle, it will act as a fender to press the flap 341 of the advancing bag downwardly in case it tends to project upward, and the small fender plate 269 will guide the advancing vertical edge of the bag outwardly of the lip plate 263, so that the latter may press the bag close to the guide plate 259. In this way, when the index motion ceases, the bag will come to rest with the tongue 203 of the bag extending across the slot 260 in the platen 251. When the glue blade is lifted it deposits a line of adhesive on the tongue of the bag centrally beneath this slot. In the event that no bag passes on any index operation, therefore, the glue blade lies within the slot clear of the platen and other parts, avoiding soiling of the machine and the work.

In case of need for removal of the glue pot, the set screw 255 may be loosened and the platen bar 261 swung back out of the way, and after loosening of the screw 268 and raising of the glue blade, the pot may be moved radially outward and upward from the machine.

As the bag moves from the gluing station, its advancing upper corner passes under the folder 279 (which is then in full raised position), owing to the fact that the major portion of the flap is still held under the platen 251 as well as by action of the tongue 294; and when the bag comes to rest at the folding station, the entire flap portion lies under the folder 279 with the score line close to the anvil 283. As before stated, the guide plate 295 will assure location of the score line close to the anvil, and when the folder swings downward the reaction of the bag flap thereagainst by inherent elasticity of the bag stock will force the score line closer to the anvil before the folder compresses the bag parts. As the high face of the folder cam 291 engages the wiper 292, the lever 289 will press the folder 285 downwardly and outwardly so that the flap of the bag is pressed tightly against the lower inner face of the bag and the glue caused to adhere firmly between the two. The interposed parts of the bag between the anvil and the folder are tightly clamped in closed position. The folder opens after a proper period of high pressure, and the next index action carries the bag from the folder station into the sealing station.

Here the conveyor 300 stands with a gap 342 therein located over the path of the carrier 95, and by means of the top guide 205 the advancing corner of the bag is pressed inwardly so that it enters the gap properly, this guide rail being located below the anvil of the folder; and an opposed fender plate 343 may be provided on the top plate 51 by which the bag top is properly held outward from the carrier 95. The index operation then brings the bag with its trailing vertical corner well within the side boundary of the conveyor, and the next operation of the opener lever 145 moves the conveyor one step, closing the gap, pressing the cemented parts of the bag top firmly therebetween, and moving the bag radially from the carrier so as to clear the path of the following bag. The bag is held compressed in the conveyor and suspended therefrom throughout a number of succeeding step movements of the index carrier 70 and conveyor, and finally, when the part of the conveyor holding the bag reaches the outer sprocket 301, the clamping members open by assuming radial position on the sprocket and release the bag. The bag then falls by gravity, and may

be caught, collected, or ordered and packed or cased by any suitable means, not shown.

For convenience in servicing the machine when slow and partial movements of the mechanism 5 may be required, the worm shaft 58 is extended rearwardly of the speed reduction case 59, and provided with a fitting 346 by which a hand crank 347 of suitable form may be applied thereto, as is familiar in various machines, and the machine 10 may then be readily operated by the hand crank to facilitate cleaning and adjustment, etc.

In order to avoid the occasional interposition of the throat edge 204 of the bag in the path of the opener and for other advantages and functions, I 15 have provided as shown in Figures 35 to 37 a pneumatic lip opener means and bag-tongue rest or stop 348. On the chute 194 a yoke 349 is mounted having arms secured to each side of the chute 194 the stop comprising a middle portion of the yoke, 20 being a flat plate 350 disposed in front of the chute, the yoke being spaced from the chute at the sides and front to afford a clear way in which the bag opener 138 may operate freely within the yoke without contacting the chute or yoke. The yoke 25 is of sheet metal and its lower edge, which comprises the stop 348 proper is positioned at a height just above the top edge of the throat or back wall of the first bag in the bag box 130, but well below the extremity of the bag tongue 203, so that when 30 the bag box is at its inner limit of movement or projected position, the tongues of the bags will be pressed outwardly by the stop 348. On the front face of the plate 350, there is secured a pressed metal shell 351 having flange portions 352 in a 35 common plane secured to the front face of the plate 350 so as to form a small flat chamber 353 within the shell, a channel in the shell 351 extending from the chamber 353 downwardly to or near to the lower edge of the plate 350 as in Figure 35, 40 to form a flat air jet or nozzle 354 communicating with the chamber 353. Through this nozzle a small stream of air may be projected downwardly just inwardly of the edge of the throat 204 of an engaged bag, as will be described. Centrally of the shell 351 a nipple 355 is fixed therethrough 45 forming communication with the chamber 353 and projecting forwardly. When a hose 356 from a compressed air supply 357 (shown formally) is engaged on the nipple, compressed air will be discharged downwardly from the nozzle. This air supply may be constant, although any automatic control coordinated with the index table may be provided if desired.

It will be noted that the opener 138 is not in this arrangement depended on to engage the 55 tongues 103 of the bags, but the stop 348 is constantly in position to engage and does engage the bag tongues when pressed inward by the box. This permits the opener to be adjusted on the rod 60 141 to bags of various depths, without regard to the action of the operating cam, to a large extent.

In the operation of this last described device, just before the index action occurs, the bag which has been filled during the immediately preceding 65 period of rest is released by retraction of the bag box to its forward position. This releases the bag tongue from between the tongue rest 348 and the following bags pressed theretoward by the box and weight of the bags in the bag box. The released bag drops between the wings 96 to rest on the pins 232 of the carrier then in proper alignment and stationary at the station. During initial index motion, the wings 96 insure movement of the bag in departure from the filling station. 70 The carrier is at this time in open position with

its wiper pressed inward by the cam track 238 holding the grip arm of the lever 234 in released position. Soon after the index motion begins the wiper 236 is thereby permitted to move outward on the outturned end of the track 238, allowing the grip arm to close on the bag as it leaves the station, and holding it securely for all subsequent operations necessary to the closing, gumming, folding, and sealing of the bag. When the bag box is initially projected to rear position, 10 the air being ejected from the nozzle 354 will at first blow upwardly from the bag, but the trap being in place, none can enter the chute 194 and if the machine is packaging fine powder the escaping air will not stir up the stock at any time. 15 As soon as the opener 138 is lowered into the bag, the plate 138 and flanges 139 will act to prevent the air from passing into the stock space in the bag, and as the nozzle is small, the spaces at each side thereof within the bag and outward of the plate 138 will be ample to vent the air without 20 tendency to pass rearwardly under the lower edge of the plate 138, which presses firmly against the front wall where the latter is supported by the following bags in the bag box. The air jet may 25 therefore be constant.

I claim:

1. A machine of the character described comprising an orbital conveyor device arranged on a horizontal orbit, means arranged along the path 30 of the conveyor device to present and open bags in erect position for filling; to feed, measure and discharge stock into opened bags; and deposit filled bags on said conveyor, means to shape and close filled bags; means to score the filled bags; 35 means to gum the filled bags; means to fold the gummed bag parts; and means to seal the folded bags; said conveyor device consisting of a rotating member, and means to operate it step-by-step, all of said means operative on bags being 40 arranged in stations spaced along the path of the conveyor and each including operating members movable into and out of the path of bags on the conveyor, said means to operate the conveyor including a vertical main operating shaft located 45 centrally within the orbit of the conveyor, and operative connections from the shaft to said means at each of said stations, the connections between the shaft and conveyor and between the shaft and all said means at said stations being 50 within the vertical projection of the orbit of the conveyor and arranged and constructed so that all will be in non-obstructing relation to bags on the conveyor at the time of step movement of the conveyor. 55

2. A machine of the character described comprising a conveyor device in the form of an annular support constructed to hold bags delivered thereto, a coaxial shaft within the conveyor, an index mechanism operatively associated with the 60 conveyor to move the conveyor step-by-step and operative connections between the index mechanism and said shaft operative within a given angle of movement of the shaft, a complete series of operating devices constructed to present, open 65 and fill a bag at one station, and to crimp, gum, and seal filled bags at succeeding stations all arranged beside the path of the bags on the conveyor and spaced to accord with the step movements of the conveyor, certain station devices including reciprocating operating members and respective cam members on the shaft operatively engaged with respective operating members and having distinct angular relation to each other, but all having inoperative relation to the re- 70 75

- spective operating members through said first named angle of movement of said shaft including the step movement of the conveyor, and operative connections between the shaft and said bag-presenting, opening and filling devices.
3. A machine of the character described comprising a conveyor in the form of a rigid annular horizontal frame element having an elevated bag support including means to support the lower edge of a bag, bag-presenting means operative radially with respect to the conveyor, to present erect open flat bags in a substantially vertical plane at right angles to a radius of the conveyor, means to open and fill presented bags and release the same over said support, said elevated support being of a height that the bags project thereabove when resting with their lower edge supported thereby, means to rotate the conveyor on its axis step-by-step, and a plurality of bag-engaging devices in respective stations of the step movement and spaced from each other beside the path of bags on the conveyor constructed and arranged to operate individually on respective bags to form, close, score, bum, fold and seal filled bags, and all arranged with engaging members at opposite sides of said path initially, means to rotate the conveyor comprising a vertical shaft concentric with said conveyor, an index device operatively connected with the conveyor and shaft, respective cams carried fixedly by the shaft and radially arranged operative connections therefrom for operating the bag-engaging devices and having such angular relation thereto and to the index device that the bag engaging devices are all clear of the path of the bags during index movement, operative connections with the shaft and said bag presenting means, and operative connections with said shaft and the bag opening and filling means.
4. A machine of the character described comprising a frame having an annular rigid conveyor frame revoluble thereon on a vertical axis, a bag carrier thereon, a concentric power shaft mounted on the frame, said conveyor having a plurality of index strikes thereon, a bar horizontally reciprocable in the frame beside the path of the strikes and having a spring-pressed latch bar movable laterally of said path and adapted to engage and push one strike on movement of the bar in one direction and to yield to the strikes on return movement of the bar, a bag box movable toward and away from the conveyor, lost motion operative connections between the bag box and bar, a horizontal cam on the shaft, a lever pivoted on the frame to swing its extremity substantially in the direction of the path of the bar and having a portion over the cam, said lever having a wiper engaged with the cam, a vertical pin on the bar, said lever having its extremity slotted to receive the pin therein, said cam having a low part within a minor angle whereby with the wiper there engaged the bar is in initial position, and a high part extending over a major angle, whereby through the lost motion connection the bag box is moved to present a bag in terminal index movement, and retracted before beginning of index movement within a small angle of movement of the shaft, a bag opening and filling means operatively associated with the bag box and operative connections therefor with the shaft operative while the said wiper on the lever is travelling the high part of the cam, a plurality of bag engaging devices arranged beside the path of bags on the conveyor spaced the distance of index movement of the conveyor, respective

cams on the shaft above the elevated rest and below the bag path, and operating members for each bag engaging device having wiping engagement with a respective cam, the cams having high parts arranged to operate the respective wipers while the wiper of said lever is travelling the high part of the first named cam.

5. A machine of the character described comprising a frame having a fixed vertical stud post, a concentric annular conveyor including a spider element revoluble on the base of the post, bag filling and working mechanisms mounted on the table, a framing above the conveyor, bag working mechanisms thereon, said bag filling and working mechanism being grouped in stations, a vertical shaft revoluble in the stud post, means connected to the shaft to rotate the conveyor step by step from station to station, a hopper spaced above the framing, agitating, measuring and bag loading means mounted in operative relation to the hopper, operative connections between said shaft and the agitating and measuring and bag loading means including a driving connection from the shaft above the post, the bag filling means including a trap normally in receiving position of a bag and yieldable thereto, a chute in receiving relation to the trap and stopping above the spider, and chute means below the spider to receive from the first named chute.

6. The structure of claim 5 in which there is mounted a fender plate above and over said driving connection inclined downwardly into discharge relation to the first named chute, and positioned to receive waste from the measure.

7. In a machine of the character described, a container presenting means, in which the container is advanced to a loading position, a stock diverting trap member mounted to lie normally in the loading position of the container, and yieldable to an advancing wall of a container moved to full loading position, the trap including a lateral projection, a loaded member slidable on the projection having a non-operative face engaging the projection throughout a predetermined movement of the trap, and having an inclined draw wiper face extending from the non-operative face upward in the direction of advancing movement of a container and the trap, whereby when the projection is past the predetermined limit of movement of the trap by a container the inclined face will draw the projection and trap further in the same direction clear of the container at loading position, and means to restore the trap and loaded member to initial position.

8. The structure of claim 7 in which said means to restore the trap and loaded member consists of a cam operatively connected with the bag presenting means, said loaded member being pivoted and having an arm extended in the path of the cam, and yielding means to hold the trap in operative position.

9. In a machine of the character described, a bag presenting means, an opener consisting of a vertically reciprocable plate having an initial raised position to receive the inner sides of a bag tongue against its outer face with the throat portion of the bag therebelow, said plate having flanges extended from the lateral edges, said flanges having lower edge portions inclined to the plane of the plate whereby to enter and press open the throat of a bag, means to feed a charge to a bag so opened, a trap device comprising a chute normally positioned beneath the

5 opener to rest against an unopened bag if presented, whereby to receive a charge, means to support the trap yieldable to a bag wall in the direction of movement of the adjacent wall of the bag when opened, a wiper on the trap, a loaded shoe mounted for vertical movement in a fixed path, and having a lower face slidable on the wiper to permit free movement of the trap by a bag, said shoe having an inner inclined face extending from the lower face and adapted to engage and slide on the wiper by the load on the shoe, to draw the trap from an engaging opened bag in the direction of opening movement of the bag wall, and means to restore the shoe to initial 10 position.

15 10. In a machine of the character described, a bag opening means including a vertically reciprocable bag opener having a lower part adapted to enter the open end of a closed flat bag the upper part of the opener being U-shaped in cross section whereby to hold open a bag and receiver therethrough a charge entering the bag, the opener including a tongue stop, a bag box adapted to hold a plurality of erect bags transversely therein and movable toward and away from the opener whereby to press the tongue of the first bag against said stop, a trap consisting of a chute adapted to normally rest against a bag below the opener, and adapted to pass within the 20 opener when lowered a spring-loaded lever connected to the trap as a support, and constructed to hold the trap at normal position yieldable to the adjacent wall of a bag when opened by the opener, a lateral pin on the trap, a loaded lever pivoted on the machine inwardly of the trap and having a shoe portion formed with a lower face initially resting on the pin and shaped to permit free movement of the pin thereagainst a predetermined distance, said shoe having an inclined face extending from the said lower face at the inner limit of said predetermined distance whereby the inclined face will engage outwardly of the pin and draw the trap away from an opened bag, said lever having a bar projected laterally a distance therefrom and offset downwardly, and a cam device having a low part adapted to allow the bar to rest thereagainst with the trap in retracted position, and a high part adapted to press the bar outwardly and raise the lever after each 25 filling operation.

30 11. In a machine of the character described, a turntable element having a plurality of strikes thereon, a bar mounted to reciprocate in a path close beside the path of the strikes, said bar being in two sections including a bar section and a latch section slidable on the bar section, a screw swivelled on one section and threaded in the other to adjust the latch section longitudinally on the bar section, a spring pressed latch pawl pivoted on the latch section adapted to swing into the path of the strikes, means to limit movement of the pawl and means to reciprocate the bar.

35 12. In a machine of the character described, a turntable element having a plurality of strikes thereon, a bar mounted to reciprocate in a path close beside the path of the strikes, a latch pawl pivoted on the bar adapted to engage the strikes, means to reciprocate the bar, a bag box reciprocable toward and away from the turntable, and lost-motion connections between the bag box and the bar constructed to move the box inward in the final movement of the bar in one direction, and to move the box outward in the final movement of the bar in the opposite direction.

40 13. In a machine of the character described, an index and bag presenting means consisting of a rotary conveyor for flat bags including a lower bag bottom rest and means to support a bag in erect position thereon, means to move the conveyor step-by-step and to present a bag over the conveyor at one point on the termination of each step consisting of a bag holding box reciprocable in a radial path and constructed to hold bags with one positioned for filling and dropping upon the conveyor in a plane at right angles to an intersecting radius, a bar reciprocable in a path of substantially greater length than a path of reciprocation of the bag box, a vertical shaft concentric with the path of the conveyor, a cam 45 thereon, a lever pivoted thereadjacent having a wiper engaging the cam to oscillate the lever, one end of the lever being adapted to swing over an arc the chord of which coincides mainly with the direction of reciprocation of the bar, operative connection between the said end of the lever and the bar, said conveyor having a plurality of spaced index elements, said bar being close beside the path of said index elements, a latch on the bar to engage and move an adjacent index 50 element under movement of the bar in one direction, and yieldable to the elements on opposite movement of the bar, an operative connection between the bag box and the bar including a separately mounted pin movable in substantially the same direction with the bar, longitudinally spaced strike blocks on the bar spaced on opposite sides of said pin, said pin being mounted for movement coincident with the path of said blocks at all times, said blocks being spaced apart more than 55 the thickness of the pin therebetween and whereby the sum of the linear spacing of the blocks and the stroke of the pin on operation of the bag box full stroke equals the full stroke of the bar.

60 14. A bag filling and sealing machine of the character described comprising a frame, an orbital conveyor thereon movable in a horizontal orbit, stock measuring and delivering means, and bag presenting, bag filling and bag working 45 mechanisms mounted on the frame, constructed, arranged and adapted to present empty bags, fill, close and seal the same, said measuring means and bag filling and bag working mechanisms being grouped in closely spaced stations 50 beside the path of the conveyor, a vertical shaft revolvably mounted centrally within the orbit of the conveyor, means within said orbit connected with the shaft to operate the conveyor step-by-step from station to station, said stock measuring 55 and delivering means being in stock delivering relation to said bag filling mechanism, operative connections within the orbit of the said conveyor between said shaft and said stock measuring and delivering means, and bag filling and bag working 60 mechanisms, and filled bag delivering means operatively associated with the said conveyor.

65 15. A machine of the character described comprising a frame, an annular bag conveyor including a spider frame revolvably mounted on the first named frame, bag filling and working mechanisms mounted in operative relation to the conveyor and grouped in stations beside the path of bags on the conveyor, means to operate the conveyor, bag filling and bag working mechanisms, a hopper above the conveyor, stock measuring means operatively associated therewith and with said bag filling means located within the orbit of the conveyor, means to operate the stock measuring means, a stock diverting trap 70

75

- device normally in receiving position of a bag at the filling station and including means to deliver stock inwardly of the path of the conveyor, stopping short of said spider, and means below said spider to receive stock by gravitation from the trap device, said machine including means to position the trap at inoperative position when a bag is in receiving position at the filling station.
16. A machine of the character described comprising a frame, an orbital bag conveyor movable in a horizontal orbital path, on the frame, bag filling and working mechanisms for closing the same mounted in operative relation to the conveyor, means within the orbit of the conveyor to operate the conveyor and the bag filling and working mechanisms, a hopper above the conveyor, stock delivering means operatively associated therewith and with the bag filling mechanism and located within said orbit, means to operate the stock delivering means, a stock diverting trap device normally in receiving position of a bag in relation to the bag filling mechanism, and including means initially positioned to deliver stock inwardly of the path of the conveyor, and means to receive stock from the trap, said machine including means to position the trap in inoperative position when a bag is in receiving position in relation to the bag filling means.
17. A machine of the character described comprising a frame having a fixed vertical stud post; a concentric annular bag conveyor revolute on the base of the post; bag filling and bag working means mounted on the frame; a framing above the conveyor and bag working means thereon; said bag filling and bag working means being grouped in stations beside the path of the said conveyor; a vertical shaft revolute in the stud post; means connected to the shaft to rotate the conveyor; a hopper spaced above said framing; agitating, measuring, and said bag filling means mounted in operative relation to the hopper; operative connections between said shaft above the post and said agitating and measuring means and operative connections between said shaft and said bag filling and bag working means, all within the path of the bags on said conveyor; a bag presenting means in operative relation to said bag filling means, and operative connections between said shaft and said bag presenting means below said conveyor and bag presenting means.
18. In a machine of the character described, means to present open end bags in a flat condition, erect at a given loading position, means to open a presented bag consisting of a bag wall engaging member movable to press one wall of the bag away from the other in a given direction, means to operate said member, means to discharge material to be loaded and to guide the discharged material in a path including the space between the walls of a bag separated as named, a diversion member movable into, and having normal position in, said path against one wall of a presented bag and adjacent the top thereof and yieldable to the said wall when the bag is opened, means to move the diversion member away from the bag at a predetermined partly operated position including an operating member constructed to engage the diversion member at said partly operated position and tending to move it to inoperative position and having inoperative position in relation to the diversion member in initial and adjacent positions short of said predetermined partly operated position, and means to release the operating member from the diversion member operatively connected to said means to open the bag.

AUSTIN S. CHANDLER. 40
